UNITED STATES PATENT OFFICE.

MARTIN M. CLAYTON, OF BADEN, PENNSYLVANIA, ASSIGNOR TO NATIONAL METAL MOLDING COMPANY, A CORPORATION OF PENNSYLVANIA.

LINER FOR ELECTRICAL CONNECTERS.

Application filed June 7, 1926. Serial No. 114,099.

It is the object of the invention to provide a liner or bore-reducer for connectors for electrical cables and conduits, which will adapt a connector of any given bore to adequately fit a conduit or cable of a smaller size than that for which it was intended, or one of a different shape, as well.

It will be understood from the following description that the invention may be utilized in connection with connectors of various types, but I have shown it in the accompanying drawings as applied to an outlet box connector of a type familiarly known as the squeeze type. Figure 1 is a view in elevation of such a connector embodying the invention. Figure 2 is a horizontal cross section on the line II-II of Figure 1. Figure 3 is a perspective view of the preferred form of liner. Figure 4 is a view similar to Figure 2, showing a modified form of liner.

The connector comprises the cylindrical sleeve portion 1, and the bifurcated extension 2, having the cooperating ears 3 and adjusting screw 4, together with the segmental slot 5, all as usual in connectors of this type. The liner 6 has a bowed or segmental body portion 7, which may terminate at one end in the ear 8, lying in the space between the ears 3 of the connector. At its inner end the body portion 7 is provided with a lug 9, so located that when the liner is slipped into the connector the lug 9 is projected outward-

ly through the slot 5. By bending the lug 9 downwardly upon the body of the connector adjacent to the slot 5, the liner will be held firmly in place. The liner may also be provided at its edge opposite lug 9 with a spacing lug 10, fitting the inner wall of the connector.

It will be understood that the specific form of the liner, as well as the size of the lug or spacer 10, may be varied as desired. It will also be evident that by the use of a suitable tool, the bent-over lug 9 may be straightened out and the liner be withdrawn from the connector.

In Figure 4 I have shown a modified form of liner which fits the entire inner face of the connector and which is provided with a lug 9, as in the other form.

I claim as my invention:

The combination with an electrical connector having a hollow cylindrical portion adapted to receive a conductor and a radial slot in its side wall, of a liner arranged between the conductor and the inner wall of the connector and having a lug projecting laterally through said slot and bent into binding engagement with the outer wall of the connector.

In testimony whereof I have hereunto set my hand.

MARTIN M. CLAYTON.
